PORATION OF DELAWARE

METHOD OF AND APPARATUS FOR MAKING AND SHAPING SOLID CARBON DIOXIDE

Application filed December 17, 1929. Serial No. 414,675.

Our present invention relates to methods and apparatus for evaporating liquid carbon dioxide to gasify part of it and freeze the remainder. Prior processes, so far as we are aware, involve intermittent operation either as to the evaporation of the liquid to form solid or as to the compression of the solid into cakes or blocks. In particular, certain prior methods that involve relatively slow boiling or evaporation of the liquid against counterpressure maintained from and at the triple point, have required relatively long intermissions between charges of liquid into the container because of the necessity of removing the solid product from the boiling chamber, either for compression in another chamber or after compression in the boiling chamber itself.

Such intermittent operation involves wide fluctuation in the demand made upon the liquefying plant and correspondingly large fluctuations in the rate at which the evaporated gas is returned to the system for recompression. Moreover, great losses result from lowering the pressure of the boiling chamber and exposing it to atmosphere, between each successive cycle of operations.

All the objectionable features above referred to are obviated by our present invention, which relates to method and apparatus whereby in a single progressive operation, liquid carbon dioxide can be continuously supplied; continuously evaporated to form solid; the solid progressively condensed to commercial density and toughness; and progressively extruded from the machine as a continuous column that can be sawed or otherwise severed into desired lengths.

While mechanical means may be used to cause or assist the extrusion, an important discovery is that pressure of the liquid source alone can be made effective for this purpose. In such case, the resistance of the formed column of solid is utilized to seal the extrusion outlet; the evaporation and solidifying is effected in the upper or inner end portion of the column; and the gas pressure there maintained is utilized to slowly force extrusion of the outer or lower end of the column. The practical advantages of this will be obvious

from consideration of the difficulties that would be involved in lubricating and maintaining moving parts at temperatures of 100° or more below zero F.

While we sometimes employ mechanism to retard or control the rate of extrusion of the column, it is not essential and when employed, is naturally located where it can be kept warm and lubricated, if necessary.

It will be noted that our above described progressive method permits of intermitting the liquid supply, and also the extrusion of the column, without entailing the losses that occur where it is necessary to open the evaporation chamber for removal of the solid.

While the principle of our invention is applicable to some extent for expansion of the liquid where the liquid from the supply is abruptly expanded to pressures below the triple point, thereby producing a solid, in snow form, precipitately, there are great advantages in having the liquid discharged into the chamber against a counterpressure above the triple point so that a supply of liquid as such is maintained on the top of the column of solid. In such a connection, an important feature of our invention consists in providing the pressure relief through which the boiled off gas escapes, in the side wall of the passage through which the column slides. In such case, the column of solid below the gas exit, between it and the extrusion exit, should be long enough and dense enough to afford a substantial seal against gas escape through the extrusion outlet. Preferably, the solidifying and sealing effect for this part of the column is insured by a slight predetermined constriction of its cross section.

The above and other features of our invention may be more fully understood from the following description in connection with the accompanying drawings, in which

Fig. 1 represents more or less diagrammatically a vertical axial section through a solidifying apparatus, showing the characteristic parts and connections;

Figs. 2 and 3 illustrate a modified form of extrusion conduit, Fig. 2 being a longitudinal section on the line 2-2, Fig. 3, and Fig. 3 a cross section on the line 3-3, Fig. 2;

Fig. 4 is a view like Fig. 1, showing a modification in which the proportions and some of the details are different from those indicated in Fig. 1;

Fig. 5 is an enlarged detail of the gas off-take shown in Fig. 1;

Figs. 6 and 7 are detail views of modified collecting grooves for the gas off-take.

In Fig. 1 there is a chamber 1 in which the solid is formed. This chamber may be of any desired cross-section, either round, square, or rectangular, but must have the proper taper and smoothness to permit the carbon dioxide formed to pass continuously out the mouth of the chamber under the pressure of the gaseous carbon dioxide above it. In a practical trial, we have used a slight flare of $\frac{1}{8}$ inch per foot, but it will be apparent that this slope necessarily varies with the size of the chambers, and for larger machines the taper may be dispensed with or even reversed.

Nozzles 2 serve to introduce liquid carbon dioxide, preferably precooled as low as practical and yet be safely above the triple point, from any suitable source. Pipe 4 may be used to conduct gas to the compression system at any convenient pressure above the triple point. In such case, screen 3 is placed in the top of chamber 1 to aid in the separation of any liquid or solid that might otherwise be entrained and carried back to the compression system.

The above described elements are the primary essentials necessary to form solid carbon dioxide in accord with our invention, and as a matter of fact even the screen 3 and pipe 4 may be dispensed with, and carbon dioxide solidified in a very simple manner. If the chamber 1 is long enough and of proper taper, it is only necessary to close the mouth of the chamber in starting with a porous plug, or in fact any kind of closure whatsoever that leaks, and introduce liquefied carbon dioxide above the triple point.

Solid will then form inside the chamber adjacent to the leaks or pores in the plug, and build a cake progressively upwards from them, the gas formed escaping downward and out through the pores of the solid already formed, and eventually out the bottom of the chamber. It will be understood that after the block of carbon dioxide is well started, it forms its own porous plug, and any closure used in starting up may be withdrawn.

An alternative method of starting up is to plug the mouth of the chamber with solid carbon dioxide from a previous run.

While the above brief description covers the main portion of our invention, it is necessary in a practical apparatus to provide means of reclaiming the gas passing down through the block of solid, and for returning it to the compression system, and it may be desirable to have auxiliary means of control-

ling the rate of withdrawal of the solid, for cutting it up, and for handling it.

The reclamation of gas is preferably accomplished in the section 5, comprising a jacket 6 and pipe 7, leading to the gas compression system, which we do not show or claim, at any desired pressure below the triple point. A perforated metal screen plate 8 serves to guide the block, but grooves and outlets as described below, may be employed.

The pipe 7 is preferably connected to back pressure regulating means as pressure gauge 7a and valve 7b or automatic means such as are well known in the art, to maintain a balanced slightly positive pressure in the section 5, for the purpose of minimizing leakage and loss of carbon dioxide gas through the lower portions of the apparatus. When it is so operated, the need for a gastight conduit at the bottom is obviated, but it will be apparent that we may operate the pipe 7 under substantial pressure by providing a gastight closure at the bottom of the apparatus, in either case reclaiming the gaseous carbon dioxide.

For removing the column of carbon dioxide as formed, we may provide means for controllably retarding the extrusion of the column and means for momentarily holding it fast above the portion to be removed, and means for sawing or otherwise cutting off said portion.

The resistance of the column of solid to downward movement may be regulated by providing a downward extension of suitable length and taper and the taper may be made adjustable by providing V-slots 15 that may be more or less narrowed by screwing clamping screw 17 in clamping collar 16.

Independently of this resistance regulation, we preferably employ the hydraulic cylinder 9 with platen 10, as a means for regulating the rate of downward movement of the column and its extrusion from the apparatus.

As means for stopping such movement of the column, we may employ movable jaws 11, which may have serrated surfaces 12 to grip the block and may be actuated by hydraulic cylinders 13. It will be apparent that a toggle or other mechanical linkage may be used in place of the cylinders without departing from our invention.

A saw 14 is provided for cutting off blocks of solid.

According to one method of operation, the platen 10 is raised into the mouth of the chamber, and the apparatus is filled with snow by maintaining the pressure throughout the apparatus below the triple point by connecting both 4 and 7 to a suitable point in the compressor system.

Pipe 4 is then throttled to build up a pressure above the triple point in chamber 1, while pipe 7 continues below the triple point, causing solidification to take place between these points. Once the block is started, plat-

en 10 is gradually withdrawn at the same rate at which solid is forming, usually about 1 inch per minute.

When the desired amount has been accumulated, movable jaws 11 are forced against the column by means of cylinders 13, holding it while the pressure of the platen 10 is relieved and a block sawed off and removed.

Platen 10 is then raised until it touches the bottom of the column of solid carbon dioxide, when the jaws 11 may be released, and the performance repeated.

In Figs. 2 and 3, we have shown a modified arrangement whereby the cross section and taper of the extrusion outlet 5 α may be varied either to predetermine any normal operating resistance of the column to extrusion or to momentarily stop the column. The advantage of this arrangement is that it dispenses with the grippers and the V-slot. As indicated, particularly in Fig. 3, the walls are of spring metal, preferably steel, and are formed or provided with wedges 17 α near the middle or springiest portion of each side wall. The cross-section is decreased at will by forcing down the rigid collar 16 α a distance which will force the wedges inward and spring the walls to the desired extent.

In Fig. 4, we have shown a simplified arrangement which can be employed for continuous operation without the use of any gripper jaws and without the necessity for using the hydraulic cylinder, except possibly for the preliminary operation of plugging up the end of the extrusion pipe to a desired height, in the manner above described.

In this Fig. 4, the proportions are those of an apparatus used for quite small scale production. The upper section 21 was about 21 inches long and had an internal diameter of 3 $\frac{3}{8}$ inches at the bottom, converging toward the top about $\frac{1}{16}$ of an inch.

The gas vent section 25 was about 8 inches long and practically uniform 3 $\frac{3}{8}$ inch diameter.

The converging terminal section 25 α was a simple cone 6 inches long, converging downward from 3 $\frac{3}{8}$ inch diameter to approximately 3 $\frac{1}{16}$ inch diameter. It was found that this relatively great length as compared with diameter imposed a sufficient resistance to downward movement of the column of frozen carbon dioxide so that the extrusion at the bottom was fairly uniform without any special adjustable controlling means.

A preferred operation was substantially the same as that described in connection with Fig. 1, except that after the apparatus was once started and in normal operation, the liquid input of gas and solid outputs were substantially constant, this, as explained above, being highly desirable for steady operation of a liquefying and recompressing plant.

In normal operation, after the column of solid has been built up a sufficient distance above the gas outlet 26, the valve 24 can be closed and valve 27 of the off-take opened. Liquid may be then supplied through pipe 22 at a pressure of, say, 300 pounds and relatively low temperature. Valve 27 will then be regulated to maintain an outlet pressure of 1 to 2 inches mercury above atmosphere on gauge 27 α , or, if preferred, a suction pump could be applied to establish a vacuum of 2 to 10 inches of mercury. The outlet pressure being thus predetermined, the operating pressure in 21, above the column, can be controlled by adjusting the valves 22 α and 24 so as to maintain a steady pressure in 21, sufficient to steadily force the column of solid downward and escape of gas through 24 and 27 can be regulated to cause boiling off and deposit of solid carbon dioxide at a satisfactory rate.

Fig. 5 is a detail view of the gas off-take on a larger scale, showing that there are a series of parallel collecting grooves 26 α leading to radial exit ducts 26 β , discharging into the collecting annulus 26 γ , which may be a casting welded to 25 as indicated.

Figs. 6 and 7 show different forms of collecting grooves. In Fig. 6 the lower surface 26 α of the groove 26 α is sloped downward in the direction of movement of the column of solid carbon dioxide for the purpose of guiding the column or particles therefrom downward.

In Fig. 7 there is a similar surface, 26 γ , except that the downward angle is steeper. Furthermore, the corresponding upper surface 26 β is undercut, the latter tending to preserve the outlet ducts 26 β from clogging.

In Figs. 1 and 4, we have indicated how taps may be arranged as strategic levels, particularly in the upper part of the apparatus for testing the presence or absence of liquid at the level of the tap. In ordinary preferred operation, it is desirable to have pressure above the triple point in the upper part of the apparatus and perfectly dry solid in the gas off-take section 5, with an intermediate zone where a body of liquid is maintained submerging the top of the column of solid and evaporating downward through the solid for exit through the lateral off-take section. The taps make it possible to determine maximum and minimum heights for the liquid because a tap at the liquid level will blow off snow, whereas a tap above or below the liquid zone will blow mostly gas with only minimum solid particles such as may be accidentally entrained.

While we have specified dimensions actually employed in a specific apparatus according to Fig. 4, it will be understood that this is merely by way of illustration since dimensions are of importance only as concerns the relative proportioning of the various parts.

of the apparatus to insure operation in accordance with the methods described. In this connection, we may note briefly that the frictional resistances to flow of solid and escape of gas, with reference to the pressure available for forcing such flow, are significant factors. As to the frictional opposition to flow of the solid, it will be noted that this varies primarily with the surface area of the inner walls of the apparatus and that this factor varies in direct proportion to the diameter and length. On the other hand, for any given internal gas pressure, the pressure available for forcing movement of the solid increases as the square of the diameter. Consequently, for increasing cross section of the apparatus mentioned in connection with Fig. 4, the flow resistance of the solid will decrease if the lengths of the respective sections and the angles of divergence and convergence are preserved. On the other hand, the increase of effective pressure area may be compensated either by increasing the lengths of the sections, increasing the convergence of the exit section 25a, or decreasing the divergence of section 21, or in a special case, making 21 converging.

While we prefer to have the extruded column dense enough to be used directly as a commercial product without further compression, it is possible and may be desirable to break up or recompress the product in a press mold such as is commonly employed for compressing carbon dioxide snow.

Furthermore, while it is preferred to operate the apparatus continuously and uniformly with a pressure above the triple point, insuring liquid at all times, in the upper part of the pressure chamber, it is possible and may be desirable to lower this pressure below the triple point, in which case there will be instantaneous jet evaporation and formation of the solid, as the liquid is discharged into this space. Such jet formation of the solid naturally occurs when the apparatus is first started up and the primary column of solid being formed, to plug the outlet passage. By proper regulation of the pressure, such jet operation may be made continuous, the column in such case naturally being relatively light and porous; and in such case the product would naturally be recompressed if intended for ordinary commercial transportation and use.

The means for limiting and controlling the rate of extrusion of the solid column, such as cylinder 9 and platen 10, for the lower end of the column, may be useful in various ways. It may be used to make the rate of extrusion more or less independent of the primary fluid pressure at the top of the column and of the flow-resistance afforded by the interior walls of the down-flow passage. In a particular case, the pressure may be made greater and the opposing resistance less than required for

normal balanced operation, as described in connection with Fig. 4. This would permit a higher rate of production of the solid.

Moreover, in normal balanced operation of the apparatus, the formation of solid at the top of the column or the downward flow, or the extrusion of the column, even though continuous, may tend to develop non-uniformities, due to special conditions, such as variations in the supply pressure from the liquefying plant, or in the back pressure on the gas line leading back to the compressors, or irregular slip of the column in overcoming the resistance to its down-flow or extrusion. While these may be corrected by more perfect design of the apparatus and regulation of the supply and vent pressures, it will be evident that irregularities of operation may be controlled directly by the above described expedient of slightly increasing the driving pressure at the top of the column or decreasing the opposing flow resistance and then opposing extrusion, and rendering uniform its rate, by means of the platen and cylinder, retreat of which is controlled at a perfectly uniform rate.

We claim:

1. A method which includes making and accumulating solid carbon dioxide by evaporating liquid carbon dioxide in a pressure chamber; affording an outlet for extrusion of the accumulated solid while opposing substantial resistance to such extrusion; and utilizing the internal pressure of gas in the chamber to compress the solid, and force extrusion thereof through said outlet against said resistance.

2. A method which includes making and accumulating solid carbon dioxide by evaporating liquid carbon dioxide in a pressure chamber; affording an outlet for extrusion of the accumulated solid while opposing substantial resistance to such extrusion; and utilizing the internal pressure of gas in the chamber to compress the solid, and force extrusion thereof through said outlet against said resistance, the internal gas pressure and the outflow counter resistance being correlated to force extrusion at a rate corresponding approximately to the rate of the formation of the solid in the pressure chamber.

3. A method of making and compressing solid carbon dioxide, which includes forming and laterally confining a column of said solid; evaporating liquid carbon dioxide to add solid at one end of said column and utilizing the pressure of the evaporated gas to compress and force extrusion of the other end of said column.

4. A method for continuous production of compressed solid carbon dioxide, which includes forming a column of said solid by discharging and evaporating liquid carbon dioxide in a pressure chamber, and controlling outlet of the gas and solid thus pro-

- duced; utilizing one end of said column as a high resistance flow path, affording back pressure sufficient to maintain said liquid carbon dioxide above triple point pressure; affording relatively low resistance outlet for escape of evaporating gas, at and near triple point pressure, at an intermediate point in said column and utilizing the internal pressure of said liquid and evaporating gas to compress and force outward movement of the column. 5. A method for continuous production of compressed solid carbon dioxide, which includes forming a column of said solid by discharging and evaporating liquid carbon dioxide in a pressure chamber, and controlling outlet of the gas and solid thus produced; utilizing one end of said column as a high resistance flow path, affording back pressure sufficient to maintain said liquid carbon dioxide above triple point pressure; affording relatively low resistance outlet for escape of evaporating gas, at and near triple point pressure, at an intermediate point in said column and utilizing the internal pressure of said liquid and evaporating gas to compress and force outward movement of the column through an outlet passage affording substantial flow resistance to such extrusion. 10. A method for continuous production of compressed solid carbon dioxide, which includes forming a column of said solid by discharging and evaporating liquid carbon dioxide in a pressure chamber, and controlling outlet of the gas and solid thus produced; utilizing one end of said column as a high resistance flow path, affording back pressure sufficient to maintain said liquid carbon dioxide above triple point pressure; affording relatively low resistance outlet for escape of evaporating gas, at and near triple point pressure, at an intermediate point in said column and utilizing the internal pressure of said liquid and evaporating gas to compress and force outward movement of the column through an outlet passage affording substantial flow resistance to such extrusion. 6. A method for continuous production of compressed solid carbon dioxide, which includes forming a column of said solid by discharging and evaporating liquid carbon dioxide in a pressure chamber, and controlling outlet of the gas and solid thus produced; utilizing one end of said column as a high resistance flow path, affording back pressure sufficient to maintain said liquid carbon dioxide above triple point pressure; affording relatively low resistance outlet for escape of evaporating gas, at and near triple point pressure, at an intermediate point in said column and utilizing the internal pressure of said liquid and evaporating gas to compress and force outward movement of the column through a remote outlet of decreasing cross section, predetermined to oppose substantial flow resistance to such extrusion and to laterally compress said column. 7. A method of making and compressing solid carbon dioxide, which includes forming a column of said solid and confining it laterally; maintaining liquid carbon dioxide at the triple point pressure at one end of said column and there evaporating it to form solid additions to said end of said column and utilizing the internal pressure of the liquid and evaporating gas to force extrusion of the column through an outlet passage at a desired rate. 8. A method which includes forming a confined column of solid carbon dioxide; applying pressure and adding solid at the upper end of said column by evaporation of liquid carbon dioxide, permitting vent of gas through an intermediate portion of said column and extruding the lower end of said column by the gas pressure on the upper end thereof and reducing the rate of extrusion to uniformity by upward pressure applied on the lower end of said column. 9. A method which includes forming a confined column of solid carbon dioxide; applying pressure and adding solid at the upper end of said column by evaporation of liquid carbon dioxide, permitting vent of gas through an intermediate portion of said column and extruding the lower end of said column by the gas pressure on the upper end thereof, and controlling rate of extrusion of the column by controlling the movement of the lower portion thereof. 10. A method which includes forming a confined column of solid carbon dioxide; applying pressure and adding solid at the upper end of said column, by evaporation of liquid carbon dioxide; permitting vent of evaporated gas through an intermediate portion of said column while extruding the lower end of said column by the gas pressure on the upper end thereof. 11. A method which includes forming a confined column of solid carbon dioxide; applying pressure and adding solid at the upper end of said column, by evaporation of liquid carbon dioxide; permitting vent of evaporated gas laterally through an intermediate portion of said column while extruding the lower end of said column by the gas pressure on the upper end thereof; and controlling the pressure and rate of column formation at the upper end with respect to the rate of column extrusion at the lower end, so as to maintain a desired length of column between the top of the column and the intermediate vent. 12. Apparatus for production, compression and discharge of a column of solid carbon dioxide, which includes a column forming mold having a pressure chamber at one end, means for supplying liquid carbon dioxide and evaporating it to form solid in said pressure chamber, upon the upper end of said column; and a mold outlet through which said column is extruded by the pressure of said evaporating carbon dioxide. 13. Apparatus for production, compression and discharge of a column of solid carbon dioxide, which includes a column forming mold having a pressure chamber for evaporating liquid carbon dioxide to make solid, a column retaining outlet passage adapted to afford resistance to escape of the solid; means for venting the evaporated gas laterally through said column, intermediate the ends of said passage. 14. Apparatus for production, compression and discharge of a column of solid carbon dioxide, which includes a column forming tubular structure having a pressure

- chamber and means for discharging liquid carbon dioxide in the upper portion thereof; an intermediate, lower level, lateral outlet for gas escaping downward from the upper portion of the column; and an open lower end adapted to reduce the cross section of the solid and thereby increase resistance to extrusion of the solid and to endwise escape of the gas through the solid.
- 10 15. Apparatus for production, compression and discharge of a column of solid carbon dioxide, which includes a column forming tubular structure having an upper pressure chamber with downwardly diverging walls and means for discharging liquid carbon dioxide therein; an intermediate portion of approximately uniform section affording lateral outlet for escape of evaporating gas; and a lower section having open lower end and converging walls to laterally compress the solid, to oppose resistance to extrusion of the solid and to endwise escape of the gas through said open lower end.
- 15 16. Apparatus for production, compression and discharge of a column of solid carbon dioxide, which includes a column forming tubular structure having an upper pressure chamber and means for discharging liquid carbon dioxide therein; an intermediate portion affording lateral, low pressure to cause evaporation of the liquid and permit escape of the gas; and a lower opening for extrusion of a column of the solid by the fluid pressure on the upper portion thereof, in combination with means for moving the walls adjacent said lower opening, to increase or decrease their convergence and vary the cross section of the extruded column.
- 20 17. Apparatus for production, compression and discharge of a column of solid carbon dioxide, which includes a column forming tubular structure having an upper pressure chamber and means for discharging liquid carbon dioxide therein; an intermediate portion affording lateral, low pressure to cause evaporation of the liquid and permit escape of the gas; and a lower opening for extrusion of a column of the solid by the fluid pressure on the upper portion thereof, in combination with laterally movable means engaging the lower portion of said column for retarding or stopping downward movement thereof.
- 25 18. Apparatus for production, compression and discharge of a column of solid carbon dioxide, which includes a column forming tubular structure having an upper pressure chamber and means for discharging liquid carbon dioxide therein; an intermediate portion affording lateral, low pressure to cause evaporation of the liquid and permit escape of the gas; and a lower opening for extrusion of a column of the solid by the fluid pressure on the upper portion thereof, in combination with a movable stop element engaging the lower end of said column and means whereby

the stop moves downward at a regulated rate.

19. Apparatus for production, compression and discharge of a column of solid carbon dioxide, which includes a column forming tubular structure having an upper pressure chamber and means for discharging liquid carbon dioxide therein; an intermediate portion affording lateral, low pressure to cause evaporation of the liquid and permit escape of the gas; and a lower opening for extrusion of a column of the solid by the fluid pressure on the upper portion thereof, in combination with a movable stop element engaging the lower end of said column and means whereby the stop moves downward at a regulated rate, which is less than the rate at which the column would be extruded by said fluid pressure.

20. A method which includes supplying liquid carbon dioxide to a compression chamber above triple point pressure, at an approximately uniform rate; evaporating said liquid at triple point to form solid and gas, and returning the gas for reliquefying at approximately uniform rate; and utilizing the approximately uniform pressure of the fluid to extrude the solid at approximately uniform rate.
